FINISHING DEVICE

Eugene I. Harrison, Downers Grove, Ill., assignor
of one-half to John J. Bailey, Chicago, Ill.

Application November 23, 1945, Serial No. 630,357

8 Claims. (Cl. 51—185)

1

This application is a continuation, in part, of my original application, Serial No. 548,770, filed August 9, 1944, which is now abandoned.

This invention relates to a finishing device for grinding, burring, and finishing material, such as metal, and particularly for use in connection with the internal surfaces of tubular articles.

More specifically, the invention relates to what may be termed an "abrasive cone" for finishing or otherwise working upon the interior surfaces of tubular members.

An important object of the present invention is the provision of a finishing device of new and novel construction, including a mandrel and a plurality of layers or plies of sheet abrasive material, the mandrel and the material being constructed and arranged to the proper size and shape, and having interengaging or interfitting construction to secure lockingly, but removably, the material to the mandrel.

Another object of the invention is the provision of a locking member or mandrel arranged and constructed so as to receive lockingly between spaced legs one or more sheets of abrasive material.

A further object of the invention is the provision of sheets of abrasive material configurated in a particular manner so as to have interlocking or interfitting engagement with a driven mandrel, and for use particularly for interiorly finishing tubes, whereby the material will assume a circular contour in cross-section when in operation.

A still further object is to provide a structure of this character having improved means incorporated therein, which will insure that abrasive elements will return to their normal or original shape, and will be prevented from becoming set in bent or distorted position, so that the same pressure upon the work will be assured, regardless of the thickness of the pad or abrading element.

A still further object of the invention consists in the provision of a finishing device for finishing metal surfaces, including grinding and burring the interior walls of a tubular member, the construction and arrangement being such that a layer, or a plurality of layers or plies, of material may be inserted readily and quickly within a driven supporting member such as a mandrel, the material being held in position by the mandrel, there being means provided to permit easy insertion and withdrawal of the material from the mandrel.

Numerous other objects and advantages will be

2

apparent throughout the progress of the following specification.

The accompanying drawing illustrates a selected embodiment of the invention, and the views therein are as follows:

Fig. 1 is a detail perspective view of the improved finishing device;

Fig. 2 is a detail sectional view on the line 2—2 of Fig. 1;

Fig. 3 is a detail sectional view showing the manner in which the device, sometimes referred to as an "abrasive cone," may be used for grinding, burring, or otherwise finishing the inside of a tubular member such as a cylinder, the device being shown in the position it assumes while being rotated in a clockwise direction;

Fig. 4 is a view similar to Fig. 3, but showing the device operating within a cylinder in a counter-clockwise manner;

Fig. 5 is a detail perspective view of the mandrel and embodying the invention;

Fig. 6 is a detail perspective view of a sheet of abrasive material which co-operates with the mandrel shown in Fig. 5, to provide an abrasive cone of the type shown in Fig. 1;

Fig. 7 is a detail sectional view on the line 7—7 of Fig. 1;

Fig. 8 is a detail perspective view of one form of locking means which may be used for securing the sheets or plies of abrasive material between the spaced legs of the mandrel; and

Fig. 9 is a detail perspective view of the reinforcing element adapted to be arranged between plies of abrasive material.

The particular construction herein shown for the purpose of illustrating the invention comprises what may be termed an "abrasive cone." The abrasive cone comprises a mandrel 1 which is provided with an elongated body 2 having spaced legs 3 to provide a central longitudinal opening

4. The exterior surface of the legs 3 is oval or substantially circular, as indicated at 5. The legs 3 are preferably formed integral with a supporting enlargement or collar 6. A shaft 7 is integral with the collar 6, and protrudes outwardly (in a direction opposite to the direction of the legs 3) to provide a shaft or stem for engagement with a driven machine part for causing rotation of the device. The space 4 between the legs 3 extends from the end 8 of an integral leg attaching part 9 to the extreme ends 10 of the device. The mandrel is preferably made from a single piece of metal, and is slotted on opposite sides, as indicated at 11, Fig. 5, forming the integral attaching portion 9, and providing the opposed slots 11. The

50
55

3

extreme outer ends 10 of the legs 3 may be relatively pointed, having rounded ends, as clearly shown in Fig. 5. Spaced alined holes 12 are formed in the legs 3 intermediate the ends thereof, to receive a locking member 13, Fig. 3, which in the present embodiment is shown as a socket head screw, known in the art as an "Allen" screw, one of the holes 12 being threaded for threaded cooperation with the threaded end 14 of the fastening member 13. The mandrel 1 is adapted to receive, in the space 4 between the spaced legs 3, a plurality of layers or plies of flexible abrasive material 15, Fig. 6. The abrasive material 15 may have abrasive applied to both sides thereof, but is shown herein as being applied to one side only, whereby there is provided an abrasive surface 16 and a smooth side 17.

The abrasive material 15 is preferably cut from conventional sheets of abrasive material, so as to provide the particular shape preferable for performing the metal removing operation on the inside of cylinders and other tubes. The material 15 is preferably provided with oppositely disposed parallel side edges 18, 18, and a straight end 19, Fig. 6. The side walls 18 converge inwardly in relatively arcuate formation, as indicated at 20, toward the extreme outer end 21. The extreme outer end may assume any configuration, as indicated at 22, Fig. 6. Each sheet or ply of abrasive material 15 is provided with a hole 23, which is adapted to aline with the holes 12 in the legs 3 of the mandrel. A centrally disposed slot 24 extends inwardly from the end edge 19 a predetermined distance, and is substantially the same size as the member 9, being adapted to receive the member 9 between the side edges 25 of the slot 24. The end 26 of the slot 24 is adapted to engage and abut the end 8 of the member 9.

A plurality of layers or plies of abrasive material 15 of substantially uniform size and configuration, are separate from each other, and when assembled in a stack are inserted between legs 3 of the mandrel, being held at their upper or inner ends by the engagement of the member 9 with the slot 24. Also, for further supporting the plies, the end 19 may abut, if desired, the inner end 27 of the collar 6. After the required number of plies or layers of abrasive material 15 is inserted between the legs 3 and properly positioned therein, with the member 9 engaging the slots 24, a fastening member 13 is inserted through the alined holes 12 and 23. The fastening member 13 is then screwed in position to draw the legs 3 tightly together and bind and removably hold the plies of material between the legs, as shown in Figs. 1, 2, and 7.

The arrangement herein shown comprises six layers or plies of abrasive material 15, although a greater or lesser number of plies may be used, depending upon the conditions or the work to be done. As shown, three layers of flexible abrasive material 15 have their abrasive surfaces 16 extending outwardly from the center, while the opposite three layers have their abrasive surfaces 16 also arranged toward the outside from the center. This construction permits the device to be used for a finishing operation, whether the device be driven in a clockwise or a counter-clockwise direction, Figs. 3 and 4. The device is particularly adapted for finishing the interior of tubes 28 such as cylinders, as shown in Fig. 3. The abrasive material 15 being flexible and the transverse dimension of the material being considerably greater than the interior dimension of

4

the tube, the sheets of material will assume, when inserted in the tube, the positions shown in Figs. 3 and 4. Because of the particular configuration of the material 15, and the fact that the plies or layers are separate from each other, the device, when in operation, will assume a relatively conical shape, the operating surfaces of the abrasive material spreading with respect to each other conforming with the shape of the tube being worked upon, and in effect forming a relatively cone-shaped member having flexible characteristics.

The abrasive material 15, particularly where the material is relatively thick, may have a smooth or non-abrasive surface 29, Figs. 6 and 7, and the longitudinal dimension of the material may extend beyond or fall short of the end 10 of the legs, if desired.

The abrasive body of the device is formed by taking two center layers and putting the smooth sides 17 in contacting relationship, with the additional layers applied on each side, with the smooth side against the adjacent abrasive surfaces 16. When so arranged in stacked formation, they are inserted between the legs to bring interengagement of the part 9 with the slot 24, and then clamped tightly together by the locking member 13. The end 7 is adapted to be inserted in a machine driven part, such as a chuck, so as to rotate the device in a clockwise direction, as shown in Fig. 3, or in a counter-clockwise direction, as shown in Fig. 4. The device is then inserted in a tube 28, whereby the flexible sheets will assume the contour or configuration of the inside of the tube, and with the abrasive material in overlapped position, as shown in Figs. 3 and 4. The overlapping is effected when the device is inserted inside of the tube. Rotation of the device, therefore, will cause the interior surface 30 of the cylinder or other tube to be finished.

It has been found that when an abrading element thus constructed has been used for a sufficient length of time, the bent or deflected portion 45 of the abrading sheets or elements, due to heat or other conditions, becomes set and will not return to its normal or original shape, with the result that when subsequently used, it is not possible to obtain the same and necessary pressure against the work or surface being operated upon. Therefore, in order to overcome this difficulty and objection, there is provided a reinforcing element 31, which is constructed of any suitable resilient material, such as spring steel or the like, which may be of substantially the same configuration as the elements 15.

The body portion of the element 31 is preferably of less width than the elements 15, so as to permit the elements 15 to be flexed or bent and, 60 at the same time, obviate the danger of the elements 15 being cut by the edge of the element 31. Furthermore, the element 31, being of resilient material, will itself be capable of being bent or flexed with the body portion of the abrading elements. With the use of this resilient reinforcing element, and after the abrading element has been used, the abrading element will be prevented from becoming set in a bent condition, under the action of heat generated by use of the device, and will, when withdrawn from the tubular work into which it has been inserted and used, operate to return the elements to their original shape. Furthermore, this resilient element 31 will insure the same pressure of the 70 abrading elements upon the inner surface of

other tubular work which may be of a larger diameter. That is, the pressure caused to be exerted by the use of the resilient element 31 will be the same. Furthermore, the edges of the abrading elements will be prevented from becoming cut by the sharp end of a tube into which the tool is inserted, as such edges will be reinforced by the resilient element. This pressure of the abrading elements against the work will be substantially the same, whether the thickness of the pad is increased or decreased.

The element 31 comprises a body portion 32, having substantially parallel sides 33, and a tapered end 34 terminating in a straight end portion 35. A recess 36 is provided in the opposite end, and an aperture 37 is also provided through the body portion.

This element 31 is of substantially the same shape as the elements 15, but its body portion is preferably narrower in width than the width of the elements 15, so as not to interfere with the deflection of the edges of the latter, and to prevent the edges of the reinforcing element from coming into contact with the surface being operated upon.

The abrasive body of the device may be formed by taking two center layers or sheets and putting their sides in proximity to each other, with the resilient element 31 therebetween, and in contacting relation with the additional layers applied on each side of the assembly. When so arranged in stacked formation, they are inserted between the legs 3 of the mandrel to bring inter-engagement of the part 9 with the slots 24 of the abrading elements 15 and the slot 36 in the resilient element 31, and are then clamped tightly together by the locking element 13, which passes through the registering openings 23 and 37. The end 7 is adapted to be inserted in a machine driven part, such as a chuck, so as to rotate the device in a clockwise direction, as shown in Fig. 3, or in a counter-clockwise direction, as shown in Fig. 4. The device is then inserted into a tube 28, whereby the flexible elements or sheets 15 will assume the contour or configuration of the inside of the tube, with the abrasive material in overlapped position, as shown in Figs. 3 and 4. The overlapping is effected when the device is inserted inside of the tube. Rotation of the device, therefore, will cause the interior surface 30 of the tube or cylinder to be finished.

The reinforcing element 31 being constructed of resilient material, will also be curved or bent with the elements 15, and will exert a pressure upon the elements to force them into contact with the surface of the work. As the resilient element 31 is of a width less than the width of the elements 15, the overlapping and deflection of the portion of the elements 15 beyond the edges of the body of the element 31 will not be interfered with. Furthermore, when the device is removed from the tube after use, the resilient element 31 will cause the sheets or elements 15 to assume, or be bent back into substantially their original shape, and thus prevent the elements 15 from becoming set in a bent condition, which otherwise they would be, by reason of the heat generated during the use of the device.

Furthermore, by providing the elements 16 and 18 separate from each other, when one or more is worn or becomes useless, it or they may be readily removed from the stack and replaced by others, without losing the benefit of those which are still fit for further use.

While the device herein shown and described is particularly adapted for the interior finishing of cylinders and other tubes, it may, of course, be used for other purposes to suit conditions. The arrangement and construction of the device is such that it will lock securely a plurality of layers of abrasive material, and maintain the layers in proper position during operation. The mandrel is preferably made from a single piece of material, and is so constructed as to permit quick and easy application and removal of the abrasive material and the reinforcing element. The mandrel and its co-operating sheets of material, as well as the reinforcing element, may be made in various sizes so as to accommodate tubes of various diameters.

The device herein shown is rigid and durable in construction, efficient in operation, and may be readily and economically manufactured.

Changes may be made in the form, construction and arrangement of the parts, without departing from the spirit of the invention or sacrificing any of its advantages, and the right is hereby reserved to make all such changes as fairly fall within the scope of the following claims.

What is claimed as new is:

1. A finishing device comprising a body having spaced legs, a lug between said legs of a thickness equal to the space between said legs, but narrower than the width of the legs, to provide a slot at two sides of the body, flexible abrasive material between said legs and having a slot inwardly from one edge to receive the lug, said legs and material having alined holes, and fastening means in said holes to lock the material to the body.

2. A finishing device embodying a body having spaced legs, a lug between said legs of a thickness equal to the space between said legs, but narrower than the width of the legs, to provide a slot at two sides of the body, flexible abrasive material between said legs and having a slot inwardly from one edge to receive the lug, said legs and material having alined holes, fastening means in said holes to lock the material to the body, a collar integral with the body and abutting the end of said material, and a protruding part extending from one end of the body and adapted for co-operation with a driven member.

3. A mandrel for a finishing device comprising a body including a pair of longitudinally extending spaced legs adapted to receive one or more layers of flexible abrasive material therebetween, means for drawing said legs together to impinge flexible material therebetween along the longitudinal axial center line of the material, when the legs are drawn together, a protruding rigid shaft secured to the legs at one end of the mandrel and adapted for co-operation with a rotatably driven device, and a lug of reduced width between said legs and integral with said legs to secure the legs together.

4. A mandrel for a finishing device comprising a body including a pair of longitudinally extending spaced legs adapted to receive one or more layers of flexible abrasive material therebetween along an axis extending longitudinally of the material, a lug of reduced width between said legs and integral therewith, whereby slots are formed on two sides of the body and into which slots the material is adapted to extend, said legs having flat inner surfaces for engagement with the material along the central axis of the material and rounded outer surfaces to add strength.

to the legs, there being aligned holes in the legs at the longitudinal central axis of the legs adapted to receive fastening means to draw the legs together to lock the material between the legs along the longitudinal center line of the material, and a shaft adapted to be driven and projecting outwardly from the legs at one end of the mandrel.

5. A mandrel for a finishing device embodying a body including a pair of elongated longitudinally extending spaced legs adapted to receive one or more layers of normally substantially flat flexible abrasive material therebetween, means for drawing said legs together to impinge the flexible material therebetween when the legs are so drawn together and with the legs contacting the outer faces of the outermost layers, integral means connecting the legs at one end adapted to be seated in recesses in one end of the material, and an integral shaft projecting outwardly at said one end and adapted for co-operation with a driven device for driving rotatively the mandrel.

6. A device for finishing an interior surface of a work article, said device embodying a holder having resilient longitudinally extending furcations and a plurality of flexible abrasive sheet elements arranged side by side and extending laterally in opposite directions beyond said holder, said sheet elements being mounted on said holder between said furcations, a sheet of springy metal arranged interiorly of the abrasive sheets, fastening means for said abrasive sheets and said metal sheet, engaging said furcations and passing through said sheets for securing the sheets in assembled relation with respect to said holder, and interengaging means at the base of said furcations and the proximate end of said abrasive sheets, for assisting in positioning said sheets between said furcations.

7. A device for finishing an interior surface of a work article, said device embodying a holder having resilient longitudinally extending furcations and a plurality of flexible abrasive sheet elements arranged side by side and extending

laterally in opposite directions beyond said holder, said sheet elements being mounted on said holder between said furcations, a sheet of springy metal arranged interiorly of the abrasive sheets, fastening means for said abrasive sheets and said metal sheet, engaging said furcations and passing through said sheets for securing the sheets in assembled relation with respect to said holder, and interengaging means at the base of said furcations and the proximate end of said abrasive sheets, for assisting in positioning said sheets between said furcations, said interengaging means embodying a lug or projection on the holder between said furcations and a recess in the proximate end of the sheets to receive said projection.

8. A finishing device embodying a body having spaced legs, a plurality of plies of flexible abrasive material arranged between said legs along substantially the center line of said pad, said plies extending laterally in opposite directions beyond said body, means engaging said legs and passing through said plies for binding the legs against the outer faces of the outermost plies, and means disposed between said legs adjacent the bottom thereof and interengaging with said plies for assisting in positioning the plies between the legs, and also assisting in holding the plies in position.
